NEUTRALIZED REGENERATIVE AMPLIFIER

Carl A. Hultberg, Buffalo, N. Y., assignor, by
mesne assignments, to Sylvania Electric Products Inc., New York, N. Y., a corporation of
Massachusetts

Application August 8, 1945, Serial No. 609,589

6 Claims. (Cl. 179—171)

1

This invention relates to regenerative circuits, and more particularly to regenerative circuits as applied to a pentode tube in a novel manner so as to obtain the benefits of regeneration without its drawbacks.

It is an object of this invention to provide a radio frequency amplifier utilizing a pentode in which the benefits of regeneration are obtained, while drawbacks are reduced.

It is a further object of this invention to provide various forms of regenerative radio frequency circuits applied to a pentode tube, in which the regeneration takes place between the anode and the suppressor grid.

It is a further object of this invention to provide a regenerative radio frequency amplifier employing a pentode in which the regenerative action takes place between the anode and the suppressor grid while a neutralizing voltage is applied to the screen grid to prevent the undesired effects of regeneration from appearing in the input circuit.

Still other objects and advantages of my invention will be apparent from the specification.

The features of novelty which I believe to be characteristic of my invention are set forth with particularity in the appended claims. My invention itself, however, both as to its fundamental principles and as to its particular embodiments, will best be understood by reference to the specification and accompanying drawing, in which

Fig. 1 is a circuit diagram of a typical pentode amplifier, showing the circuit elements, to which consideration is given, and from which the operating conditions desired may be better understood.

Fig. 2 is one form of improved circuit in accordance with this invention.

Fig. 3 is a somewhat modified form, and

Fig. 4 is a still further modified form.

In the various figures, like reference numerals indicate like parts.

Referring now more particularly to Fig. 1, a typical pentode may comprise cathode 10c, control electrode 10g, screen electrode 10sc, suppressor electrode 10sr, and anode 10a. The input circuit may be connected between the control electrode and cathode, and control voltage E1 is impressed thereon.

Various significant capacities usually inherent in the construction of the tube and the wiring attached thereto are indicated, such as C1, the control grid-cathode capacity; C2, the capacity between screen 10sc and control grid 10g; capacity C3 between suppressor 10sr and control elec-

trode 10g; and capacity C4 between anode 10a and control electrode 10g.

For purposes of analysis, with the tube in operating condition, various voltages exist between the various electrodes and the cathode, among which may be E2, the voltage from screen 10sc to cathode 10; voltage E3 from suppressor 10sr to cathode 10c; and voltage E4 from anode 10a to cathode 10c.

10 In accordance with my invention, regeneration is employed in a pentode by coupling the anode circuit to the suppressor circuit, and a voltage of proper magnitude and phase may also be applied between screen 10sc and cathode 10c, so that the admittance of the control grid-cathode circuit is substantially the same as if no voltage were present on suppressor 10sr or anode 10a. In other words, viewed from the input terminals, the input circuit of the tube has the same constants as if no regeneration were employed, whereas ordinarily the application of regeneration to a tube results in an effective reduction of the impedance and/or resistance of the input circuit. This may adversely affect the operation of preceding circuits.

15 This condition, in which regeneration is applied from the anode to the suppressor circuit while a voltage is applied to the screen to prevent undesired regenerative effects in the input circuit, I term neutralization. I am aware that this term has previously been used to describe triode arrangements in which various forms of reverse feedback have been employed to prevent or control undesired oscillation, but the term as used herein has a different meaning, as given above.

20 Referring now more particularly to Fig. 2, in which I have shown the application of the principles of my invention to one form of pentode circuit, the pentode contains the same elements as shown in Fig. 1. Cathode 10c may be connected to ground through resistance 11 shunted by bypass condenser 12. The anode may be connected to a tuned circuit made up of inductance 13 and variable condenser 14, and the B supply obtained through source of plate potential 15, the negative terminal of which may be grounded.

25 The radio frequency voltage developed in tuned circuit 13—14 may be applied to suppressor 10sr through condenser 16, which may be also connected through resistance 17 to ground. Screen 10sc may be coupled through inductance 19 to inductance 13, and connected through suitable source of potential 18 to ground, thus main-

taining it at a positive potential with respect to cathode. The input voltage may be impressed between control electrode and ground, and the output voltage taken between anode and ground at the output terminals.

If the output circuit contains a load, the A. C. plate voltage can be completely expressed as $E4 = (M+jN)E1$ in terms of the input voltage. For constant regeneration, $E3 = -KE4$ for neutralization as above defined. Voltage $E2$ may be impressed on the screen, and this will be a fraction of $E4$; for instance, $E2 = WE4$. Then the input admittance is

$$Y = jw[C1 + \{1 + W(M+jN)\}C2 + \{1 - K(M+jN)\}C3 + \{1 + M+jN\}C4] \quad (1)$$

Let Y_0 equal the admittance when $E2$, $E3$, and $E4$ are zero.

For the purposes of this discussion, A. C. values only need be considered. W may have any + or - value, and in some cases may even be zero. The optimum value of W is obtained by equating Y_0 to Y of Equation 1.

$$Y_0 = jw(C1 + C2 + C3 + C4) \quad (2)$$

This yields

$$W(M+jN)C2 - K(M+jN)C3 + (M+jN)C4 = 0 \quad (3)$$

Since the phase angle

$$\tan^{-1} \frac{N}{M}$$

is common to all terms, we can simplify and obtain

$$WC2 - KC3 + C4 = 0 \quad (4)$$

from which

$$W \frac{KC3 - C4}{C2} \quad (5)$$

In order for perfect neutralization to take place, the voltage sources for $E2$ and $E3$ voltages should have negligible impedance to the current. In general this condition may be closely approached by the circuit shown in Fig. 2. Since $C2$ is many times larger than $C3$ and $C4$, W will in general be much smaller than K . If this were not true, then W would be so large that it would cause the net plate circuit feedback to be degenerative rather than regenerative.

Referring now more particularly to Fig. 3, in this instance the plate voltage may be obtained by the connection of the plate source to one side of tuned circuit 13-14 rather than to an intermediate point on inductance 13 as in Fig. 2, and condenser 16 may be connected to one terminal of inductance 19 instead of to inductance 13. Screen source 18 may be connected to an intermediate point on winding 19. Otherwise the circuit is substantially the same as that shown in Fig. 2, and no further description is believed to be necessary.

Referring now more particularly to Fig. 4, I have shown still a further modification, in which resistance 17 and condenser 16 may be omitted. In this instance the plate circuit arrangement is the same as that of Fig. 3, but screen 10sc may now be connected through winding 19, as in Fig. 2, winding 19 being coupled to inductance 13 and connected through source 18 to ground.

An additional winding 21 may be provided, connected at one end to suppressor 10sr and through an additional source of biasing potential 20 to ground, or directly to ground through contact 23. Switch 22 may be employed if desired, to permit connection of suppressor 10sr either di-

rectly to ground or to ground through source 20.

In any case, however, it will be observed that the circuits of Figs. 2, 3, and 4 operate to apply a regenerative voltage to suppressor 10sr from the plate circuit, and that they also apply to screen 10sc neutralizing voltage which prevents the input circuit of the tube being affected by the regenerative action, thus making it possible to utilize the benefits of increased gain and selectivity obtainable from regeneration without the reduction of resistance or impedance of the input circuit, which might interfere with or reduce the efficiency of circuits feeding the input circuit.

In the specification I have explained the principles of my invention and the best mode in which I have contemplated applying those principles, so as to distinguish my invention from other inventions; and I have particularly pointed out and distinctly claimed the part, improvement, or combination which I claim as my invention or discovery.

While I have shown and described certain preferred embodiments of my invention, it will be understood that modifications and changes may be made without departing from the spirit and scope thereof, as will be clear to those skilled in the art.

I claim:

1. The combination with a vacuum tube having a cathode, an anode, and at least three grid electrodes between cathode and anode, of a tuned circuit connected between cathode and anode, means for impressing a voltage derived from said tuned circuit between cathode and the grid electrode nearest the anode to produce regeneration, means for impressing a voltage of different phase between cathode and the next successive electrode nearest the anode to neutralize in the cathode-control electrode circuit the regenerative effects of the first voltage, and an input circuit connected between cathode and the third grid.

2. The combination with a vacuum tube having a cathode, an anode, a control electrode, a screen electrode, and a suppressor electrode, of a tuned circuit connected between cathode and anode, means for impressing a voltage derived from said tuned circuit between said cathode and said suppressor electrode to produce regeneration, means for impressing a second voltage of different phase between said cathode and said screen electrode to neutralize in the cathode-control electrode circuit the effects of regeneration, and an input circuit connected between cathode and the control electrode.

3. The combination with a vacuum tube having a cathode, an anode, a control electrode, a screen electrode, and a suppressor electrode, of a tuned circuit connected between anode and cathode, a first inductance coupled thereto and connected between the suppressor and cathode to apply to said suppressor electrode a voltage of opposite phase to that at said anode, a second inductance coupled thereto and connected between the screen electrode and cathode, the voltages of said last two mentioned inductances being of substantially opposing phase to neutralize in the cathode-control electrode circuit the regenerative effects of said first-mentioned voltage, and an input circuit connected between said cathode and said control electrode.

4. The combination with a vacuum tube having a cathode, an anode, a control electrode, a screen electrode, and a suppressor electrode, of a tuned circuit including an inductance connected between cathode and anode, a connec-

tion from an intermediate point on said inductance to the cathode, a connection from one end of said inductance to the suppressor electrode, said connection including a capacity, a second inductance coupled to the first inductance and connected between the screen electrode and cathode and an input circuit connected between cathode and the control electrode.

5. The combination with a vacuum tube having a cathode, an anode, a control electrode, a screen electrode, and a suppressor electrode, of a tuned circuit connected between anode and cathode, said tuned circuit including an inductance, a second inductance coupled to said first inductance, said second inductance having its opposite terminals connected to the screen and suppressor electrodes with the screen-electrode terminal of the same polarity as the anode terminal of said first-mentioned inductance to neutralize in the cathode-control electrode circuit the regenerative effect of the voltage applied by said second inductance to said suppressor electrode, said latter connection including a capacity, a connection from an intermediate point of said second inductance to said cathode, and an input circuit connected between cathode and the control electrode.

6. The combination with a vacuum tube having a cathode, an anode, a control electrode, a

screen electrode, and a suppressor electrode, of a tuned circuit connected between anode and cathode, said tuned circuit including an inductance, a second inductance coupled to said first inductance and connected between the suppressor electrode and cathode, a third inductance coupled to said first inductance and connected between screen electrode and cathode, the coupling relations between said inductances being such that the voltages of said anode and said screen-electrode are substantially in phase and the voltages impressed between suppressor and cathode and screen and cathode are out of phase to neutralize in the cathode-control electrode circuit the regenerative effect of the voltage supplied to said suppressor electrode, and an input circuit connected between said cathode and said control electrode.
